UNITED STATES PATENT OFFICE.

GEORGE RICHARDS AND LESLIE NEWMAN BURT, OF WESTMINSTER, LONDON, AND JAMES EDWARD FREEBORN, OF WALTHAMSTOW, ENGLAND, ASSIGNORS TO THE RICHARDS THREAD MILLING MACHINE COMPANY, (1918,) LIMITED, OF WESTMINSTER, LONDON, ENGLAND.

MILLING SCREW-THREADS.

1,386,279.

Specification of Letters Patent.

Patented Aug. 2, 1921.

Application filed April 8, 1920. Serial No. 372,315.

To all whom it may concern:

Be it known that we, GEORGE RICHARDS, a citizen of the United States, and LESLIE NEWMAN BURT, a subject of the King of Great Britain and Ireland, both residing at The Outer Temple, 222 Strand, in the city of Westminster, London, England, and JAMES EDWARD FREEBORN, a subject of the King of Great Britain and Ireland, residing at 2 Elmsdale road, Walthamstow, in the county of Essex, England, have invented new and useful Improvements in Milling Screw-Threads, of which the following is a specification.

15 This invention relates to an improved method of cutting screw-threads with the aid of what are known as "hobs"; that is to say, rotary cutters wherein the cutting teeth follow spiral lines having a pitch corresponding with that of the thread to be formed.

It has hitherto been the practice to impart to the hob and to the work-piece the same rotative speed, but neither partakes of any axial movement. Under such conditions, it is necessary to make special provision for elimination of facets, which result from the cutting teeth coming successively into operation upon the work at the same 25 points in successive revolutions. There is, moreover, the objection that the portion of the work-piece threaded is restricted in length to that of the hob. A further objection is that, when using a multiple-thread 30 hob, difficulties occur in shaping the toothed thread on the hob in such a manner as to cut, in the work, a thread of the correct shape.

With a view to avoiding these objections, 40 we mount the hob-spindle in a frame capable of being canted; such frame being mounted on a slide, so as to admit of the hob being advanced laterally toward the work-piece with a view to cutting the thread 45 in the latter to the required depth. The said slide is in turn mounted on a saddle, adapted to be traversed upon the bed of the machine, and is provided with a screw of predetermined pitch for effecting such movement. When the hob-spindle is tilted in a 50 vertical plane, and when extreme accuracy is required in the form of the thread cut,

the surface of the hob is made slightly curved in a longitudinal direction, or, for internal work, slightly barrel-shaped.

55 The work-spindle, which is mounted in the headstock of the machine, is in gear with the hob-spindle; these two spindles revolving, contrary to the usual practice, at slightly different speeds. The work-spindle is also 60 in gear with the screw which operates the traverse slide, the pitch of the said screw, or the gearing whereby it is driven, being proportioned to the difference between the 65 rotative speed of the work-spindle and that of the hob-spindle.

Under such conditions, by reason of the axial advance of the hob in relation to the work, the rotative speed of the former, or of the latter, being varied to suit, we are able 70 to screw-thread portions of the work the length of which considerably exceeds that of the hob. Moreover, as work-threads cut by the leading hob-threads are subsequently 75 operated on by the following hob-threads, any facets formed by the leading hob-threads become eliminated.

The provision of substantial and rigid support for the cutter-spindle is of importance, and is facilitated by the employment 80 of a taper hob.

One mode of constructing apparatus adapted for use in carrying our invention into effect is illustrated in the accompanying drawings, whereof Figure 1 is a vertical 85 section of part of the gear employed to drive the cutter spindle, Fig. 2 being a partly diagrammatic end elevation illustrating gears arranged between the latter and a traversing shaft hereinafter referred to. Fig. 3 is a part plan illustrating certain 90 further details of the traversing mechanism, while Figs. 4 and 5 are part views in plan illustrating the application of our invention where a taper hob is employed. Figs. 95 6 and 7 are respectively a sectional plan and a front elevation showing the general arrangement of the apparatus, while Fig. 8 is a diagrammatic view illustrating certain further gearing hereinafter described.

100 By transmitting to the cutter-spindle by way of a suitably arranged differential gear, the rotative movement which is imparted to the carriage-traversing mechanism, the hob

may be speeded up, or retarded, according to the direction of travel, in such a manner that the relation between the hob-threads and the threads on the work remains undisturbed when the hob is moved longitudinally; thus enabling the work-piece to be screw-threaded over a length greatly exceeding that of the hob.

As shown in Fig. 1, the drive is transmitted from the back-shaft *a* to a worm-wheel *a*¹ mounted on a bearing attached to a saddle *b*. In a suitable bracket *b*¹ mounted upon the worm-wheel *a*¹ and able to revolve with the latter, is arranged a short shaft *c* whereon are freely mounted two similar bevel-wheels *c*¹, *c*², which mesh with a bevel-wheel *d*, mounted on a shaft *d*¹, whereof the outer extremity carries a spur-wheel *d*².

The bevel-wheels *c*¹, *c*², also mesh with a further bevel-wheel *e*, mounted upon a cross shaft *f*, from which the cutter spindle is driven. From the back-shaft *a* driving the worm-wheel *a*¹, the drive is transmitted to the cross-shaft *f*, by way of the bevel-wheels *c*¹, *c*², meshing with the bevel-wheel *d*, and thence to the bevel-wheel *e*, which is fast upon the cross-shaft *f*; the bevel wheel *d* remaining locked when, as in cutting a short length of screw-thread no traverse of the hob is effected.

The traverse of the saddle *b*, and hence that of the hub, is effected by transmitting the power supplied by the back-shaft *a* through suitable gears *g*, *g*¹, *g*², as shown in Fig. 2, to drive the worm-shaft *h*, at a suitable speed; provision being made for throwing these gears into and out of engagement. The worm-shaft *h*, carries a worm *h*¹ which meshes with a worm-wheel *h*², the boss of which is internally screw-threaded to form a nut adapted to traverse the lead-screw *j*, which is held against rotation. The outer extremity of the worm-shaft *h*, carries a spur-wheel *h*³, which, as shown in Fig. 3, meshes with the spur-wheel *d*², through one or more suitable idlers, such as *d*³; provision being, moreover, made for varying the said spur-wheels and idlers in order to establish different speed ratios adapted to produce threads of the particular form required.

Short lengths of thread, less than or equal to the hob in length, may thus be cut without any endwise motion of the saddle *b*, when the feed drive is, by any suitable means, thrown out of engagement; but should a "creep" motion be required in these short lengths of thread, a hand-lever may be attached to the front end of the worm-shaft *h*, and the required "creep" be produced by hand.

As an alternative, the lead-screw may be driven in conjunction with similar gear to produce the same effect; or the lead-screw

may be driven direct producing a different speed ratio from that of the hob, as in Fig. 5.

In order to permit of the cutter-spindle being rigidly supported, a taper hob may be employed, so as to permit of the carriage assuming an angular position in relation to the work; thus providing the necessary clearance for a substantial and steady carriage, as shown in Figs. 4 and 5.

To enable the hob to assume the correct position for the teeth to cut in the path of the helix angle of the thread on the work, the saddle *b* is, as shown in Fig. 6, mounted on a bed *k* and carries a cross-slide *l* which may be moved laterally, to obtain various depths of thread, by means of a screw-spindle *m*.

The cross-slide *l* carries a pivotally mounted carriage *n*, arranged vertically in relation to the bed *k*, and adapted to rotate about the center *k*¹, as shown diagrammatically in Fig. 8, in order to adjust the axis of the hob to any angle required.

The carriage *n* which supports the cutter-spindle *p* may, by means of the screw *o* and hand-wheel *o*¹, be adjusted vertically on slides carried by the pivotally mounted carriage *n*, as illustrated in Fig. 7. The drive for the cutter-spindle *p* is imparted, as shown in Fig. 6, from the cross-shaft *f* through suitable spur-wheels *p*¹, *p*², *p*³, *p*⁴, whereof the last indicated is free to revolve about the center *k*¹, whereon the spur-wheel *p*³ is mounted.

The spur-wheels *p*¹, *p*², *p*³, are mounted in the cross-slide *l*; the spur-wheel *p*¹ being free to slide upon a spline along the cross-shaft *f*.

The spur-wheel *p*⁴, drives the worm-shaft *r* shown in Fig. 6, and thence, by way of the worm *r*¹ and the worm-wheel *s*¹, the vertical shaft *s* upon which the worm-wheel *t* is free to slide vertically upon a spline, as shown in Fig. 7; the cutter-spindle *p* being driven by means of a worm-wheel *x* mounted at its extremity and meshing with the worm-wheel *t*.

Under such conditions, the hob-teeth may be adjusted to cut along any angle required to conform with the helix of any particular thread. Furthermore, on reaching the end of the thread when using a parallel hob, the carriage *n* may be fed downward to finish those threads, which, by reason of the end of the hob being canted above the work-center, have been left unfinished.

We claim:—

1. The herein described method of milling screw-threads with the aid of a hob, consisting in imparting to the hob a gradual axial motion, the relative rotative speeds of the hob and of the work-piece although nominally equal being suitably adjusted to compensate for the axial motion of the hob.

2. The herein described method of milling screw-threads with the aid of a hob, consisting in imparting to the rotating hob a gradual axial motion and imparting to 5 the work-piece an additional relative rotative speed of one revolution for each advance of the hob for a distance equal to the pitch of the thread cut.

3. The herein described method of milling screw-threads over a length substantially 10 greater than the axial length of the hob employed consisting in mounting a taper hob

on a spindle inclined to the axis of the work-piece and borne in a traversing carriage to which a gradual longitudinal motion is imparted; the relative rotative speeds of the hob and of the work-piece, although nominally equal, being suitably adjusted to compensate for the longitudinal advance of the hob. 15
